UNITED STATES PATENT OFFICE.

LUTHER J. ISENHOUR, OF INDIANAPOLIS, INDIANA, ASSIGNOR OF SEVEN-EIGHTHS
TO JACOB WOHLFELD, OF INDIANAPOLIS, INDIANA.

CORN-POPPING MACHINE.

Application filed June 16, 1920. Serial No. 388,476.

To all whom it may concern:

Be it known that I, LUTHER J. ISENHOUR, a citizen of the United States, residing at Indianapolis, in the county of Marion and 5 State of Indiana, have invented a new and useful Corn-Popping Machine, of which the following is a specification, reference being had to the accompanying drawings and to the letters and figures of reference marked 10 thereon.

This invention refers to a machine or apparatus of the type that is designed for popping corn, especially in small quantities and continuously as may be required to be sold 15 at retail, whether in-doors or out in the open air where exposed to various atmospheric or climatic conditions, the invention having reference more particularly to incased corn-popping apparatus comprised in a machine 20 which may be either portably or stationarily arranged for use.

An object of this invention is to provide a corn-popping machine of improved construction which shall be sanitary and permit 25 the operations to be inspected, and which shall be so constructed as to be not only meritorious in its practical operation but educational and amusing to observing patrons.

Another object is to provide an improved 30 corn-popping machine which shall be so constructed as to be capable of efficiently separating properly the popped corn from the unpopped or shot corn and delivering the popped corn ready to be dispensed.

35 A further object is to provide an improved corn-popping machine having particularly advantageous arrangements of various elements designed for carrying out different steps in the corn-popping operations, 40 so as to insure superior results.

Still further objects are to provide an improved apparatus whereby to feed unpopped corn to a heated table and to automatically control the feeding of the corn; to provide 45 improved means whereby to agitate and control the corn while being popped on the table; to provide improved means whereby to control delivery of the corn from the heated table; to provide improved means 50 whereby to separate the popped from the shot corn; and to provide improved means for buttering and finally discharging the popped corn.

Another and important object of the invention is to provide a corn-popping machine of improved construction generally and having adjustable features to effect accurate and easy operation of the machine and to insure durability and economy in operation, while being of simple construction 60 as to details and permitting construction at a minimum cost.

With the above-mentioned and other objects in view, the invention consists in a corn-popping machine having various novel 65 and improved elements or devices, and improved automatically-operating devices whereby to obtain the improved results sought; and, the invention consists further in the parts and combinations and arrangements of parts as hereinafter particularly described and further set forth in the accompanying claims.

Referring to the drawings, Figure 1 is a rear elevation of the corn-popping machine 75 as preferably constructed, the supporting stand and the rear door of the machine being broken away. Fig. 2 is a plan of one of the operating devices of the machine, on an enlarged scale. Fig. 3 is a plan on a relatively 80 smaller scale of a device designed to be used in connection with the device shown in the preceding figure. Fig. 4 is an elevation of the main part of the agitator that co-operates with the heated or popping-table. Fig. 85 5 is a fragmentary perspective view of associated elements of the buttering apparatus. Fig. 6 is a vertical central sectional elevation of the improved machine, transversely of Fig. 1. Fig. 7 is a top plan of the feeding- 90 chute which is adapted to constitute a frame or housing for various operating devices of the machine. Fig. 8 is a fragmentary sectional elevation showing the main structure 95 of the machine looking rearwardly, approximately on the line VIII—VIII in Fig. 6, the rear door being omitted. Fig. 9 is a fragmentary transverse section of the main portion of the corn-separator. Fig. 10 is a fragmentary front elevation of the feed- 100 chute and operating devices thereon. Fig. 11 is a vertical central section of the upper portion of the feed-chute. Fig. 12 is a fragmentary vertical central section of the feed-chute at right angles to the preceding figure. Fig. 13 is a fragmentary vertical sectional 105

elevation of the main associated parts of the machine looking forwardly, approximately on the line XIII—XIII in Fig. 6, portions of elements being broken away to expose other portions. Fig. 14 is an inverted plan of the principal elements of the agitator. Fig. 15 is a plan of one of the structural features of the agitator. Fig. 16 is a fragmentary sectional detail view of the devices for operating the agitator. Fig. 17 is a sectional elevation of the improved buttering apparatus. Fig. 18 is a bottom plan of the improved feed-chute. Fig. 19 is an end elevation of the associated popping-table and agitator. Fig. 20 is a horizontal sectional plan of the improved machine approximately mid-way of the top and the bottom of the feed-chute. Fig. 21 is a top plan of the improved corn separating structure. Fig. 22 is a top plan of the main part of the agitator. Fig. 23 is a top plan of the butter box and apparatus thereof; and Fig. 24 is a top plan of the improved machine partly broken away.

25 The reference characters corresponding in the different figures of the drawings indicate corresponding elements or features of construction herein referred to in detail.

As preferably constructed the improved 30 corn-popping machine has a suitable stand 1 provided with a top 2 which constitutes the floor of a main housing for the required mechanism, the housing suitably comprising corner posts 3, 4, 5 and 6, erected on the 35 floor, a top frame 7 supported on the posts, and a roof plate 8 supported upon the top frame and having preferably a down-turned flange 9. The housing has a front wall 10 and side walls 11 and 12, preferably composed of glass, and a rear door 13 to permit 40 the operator to have access to the interior of the housing.

A corn-box and hopper is provided and 45 comprises a base frame 14 having legs 15, 15', secured upon the roof plate 8, and a glass wall 16 upon the base frame. The base frame supports a hopper bottom 17 having a discharge pipe 18 arranged on one side of the central portion of the bottom. 50 Preferably the corn-box is covered, and in such case a securing rod 19 is secured vertically to the middle portion of the bottom 17, an apertured cover part 20 is seated upon the glass wall and suitably secured in place 55 by the rod 19, and a lid 21 is removably arranged on the cover part 20 to close the aperture therein. The base frame 14 has shaft hangers 22 and 23 in which a shaft 24 is rotatably mounted horizontally. A pulley 60 25 is secured to the shaft beyond the outer side of one of the hangers, a washer 26 is arranged on the shaft between the pulley and the adjacent one of the hangers, and a similar washer 27 is arranged on the shaft 65 at the outer side of the opposite hanger, the

washers being composed of non-metallic material such as vulcanized fiber to provide noiseless end thrust bearings, a cap nut 28 being screwed to the shaft in contact with the washer 27 and having a set-screw 29 70 therein engaging the adjacent end of the shaft to adjustably take up end play of the shaft. A suitable electric motor 30 is mounted upon the roof plate 8 and has a driving shaft 31 which is provided with a pulley 32 75 whereby the pulley 25 is driven by means of a belt 33 connecting the pulleys. The shaft 24 has a worm 34 fixed thereto for transmitting motion.

The apparatus includes a novel feed-chute 80 35 which is rectangular in cross section and vertically arranged with its top beneath the discharge pipe 18, one side of the feed-chute having projecting journal boxes 36 and 37 thereon adjacent to its upper and lower ends 85 respectively, and the upper journal box and the adjacent portion of the feed-chute have a flange 38 thereon that is arranged beneath the roof plate 8, the latter having a suitable opening receiving the feed-chute and the 90 journal box. A suitable gasket 39 is arranged upon the roof plate to exclude rain water from the opening in the roof plate, the gasket and flange being secured to the roof plate by means of bolts 40. The flange 95 has ample dimensions so as to rigidly support the feed chute. A driving shaft 41 is rotatably mounted vertically in the journal boxes 36 and 37, and the shaft has a worm gear 42 fixed thereto above the upper journal 100 box and in engagement with the worm 34. A bevel pinion 43 is secured to the driving shaft at a suitable distance below the upper journal box. The lower portion of the driving shaft has a crank arm 105 44 secured thereto beneath the lower journal box, and the crank arm is provided with a crank pin 45 which preferably is composed of a number of parts and so as to have a roller provided with anti-friction ball 110 bearings. The side of the feed-chute is provided with a stub shaft 46 at a suitable distance lower than the pinion 43 and it rotatably supports a spur-tooth pinion 47 and a bevel gear wheel 48 fixed to the pinion, the 115 gear wheel being in mesh with the pinion 43 for transmitting motion.

The upper portion of the feed-chute has a plurality of elastic fingers 49 in one side and similar fingers 50 at the opposite side of the 120 interior thereof, and in inclined arrangement; the upper portions of the fingers being secured to the feed-chute wall so that the fingers shall extend downwardly and each series of fingers towards the opposite series 125 of fingers, the lower end portions of the fingers preferably being curved backwardly. The fingers are flat-faced and designed to assist in controlling the feeding of the corn. A feed-shaft "51" is arranged to extend hor- 130

izontally through the feed chute and is rotatably supported in the opposite wall portions thereof, and it has a gear wheel 52 fixed on one projecting portion thereof and 5 in mesh with the pinion 47. The feed-shaft has a longitudinal groove 53 in its side and a pulley 54 secured to the opposite projecting shaft portion, the pulley having an eccentric 55 fixed on its rear side and a hollow 10 journal 56 on the rear side of the eccentric, the journal being rotatably supported in the adjacent portion of the feed-chute wall to support the adjacent portion of the feed-shaft. The pulley has a groove 57 in its periphery to receive a driving belt in case it be desired to drive a fan or other devices in the housing. The pulley is preferably secured to the feed-shaft by means of a set-screw 58. The feed shaft extends between the two series 20 of fingers in the feed-chute, and the groove 53 is designed to receive and feed the grains of corn past one series of fingers while the opposite series of fingers retains the remainder of the corn upon the feed-shaft. 25 For the purpose of varying the quantity of corn fed at each revolution of the feed-shaft, a core 59 is arranged in the groove 53 and is adjustable longitudinally so as to fill a portion of the groove and leave an unobstructed 30 portion to receive the corn. The outer end of the core has a handle 60 thereon, and the outer side of the core has notches 61 therein to receive a plunger-ball 62 arranged in the pulley 54 and provided with a spring 63 to 35 force it to the core, the plunger-ball being forced out of the notches when the core is forcibly moved longitudinally.

A controller shaft 64 is rotatably supported horizontally in opposite portions of the feed-chute wall, below the feed-shaft, and extends through the feed-chute, one extending portion of the shaft having a ratchet wheel 65 fixed thereto at the outside of the feed-chute. A friction disk 66 is secured to the shaft 64 within the feed-chute and has frictional contact with the adjacent wall portion thereof, being yieldingly held in place by a spring 67 seated on the opposite wall portion. A hub 68 is rotatably arranged on the shaft 64 at the outer side of the ratchet wheel and has an arm 69 fixed thereon that extends upward and has a fork 70 engaging the eccentric 55 whereby to oscillate the arm, the arm being provided with a pawl 71 engaging the ratchet wheel whereby to periodically turn the controller shaft. The hub has also a suitable longer oscillatory arm 72 thereon which extends downward and has a connecting-rod 73 pivoted thereto, the end of the connecting-rod being provided with a hook 74 set so as to have an open under portion. The purpose of the arm and connecting-rod will appear hereinafter. A dumping-gate 65 75 is arranged in the lower portion of the

feed-chute and has a hinge portion 76 connecting with the wall of the feed-shaft at the forward portion thereof, the gate extending at an inclination downward to the rearward side of the feed-chute. A controlling arm 77 is fixed to the hinge portion of the gate and extends horizontally outward through an opening in the adjacent wall portion, and it has a weight element 78 thereon to hold the gate in closed position. 75 A link 79 is loosely connected with the arm 77 and extends upward and is connected pivotally with a cam-arm 80 which is provided and supported by a pivot 81 on the forward side of the feed-chute. The cam-arm 80 has a projection 82 on the under portion thereof and arranged adjacent to the shaft 64, and the shaft is provided with a lateral finger 83 arranged to be brought into engagement with the projection 82 to operate 85 and then quickly release the cam-arm 80. A yoke is provided which comprises two arms 84 and 85 and a cross-bar 86 connected to one end of the arms, the arms being pivoted to the opposite outer sides of the feed-chute approximately on the plane of the shaft 64, the arms extending forward horizontally, and one of the arms has a projection 87 on its inner portion arranged to be engaged by the finger 83 for lifting the 90 yoke and permitting it to drop quickly. A link 88 is pivotally connected to the cross-bar 86 of the yoke to operate a device hereinafter described as associated with the popping apparatus. 100

A popping-table is provided which is composed of a rectangular top plate 89 and downwardly extending ends 90 and 91 provided with ears 92 and 93 respectively, the top plate having also downwardly extending sides 94 and 95 and an intermediate wall 96 a short distance back from the front side 94 to provide a discharge opening. The top plate 89 is inclined so that the corn thereon may be worked over to the discharge opening. The top plate has downwardly extending portions 97 and 98 arranged with a space 99 between them so that the corn shall slide downward from all portions of the discharge opening to a central point and emerge through the central space. A plurality of hanger rods 100 and 101 are rigidly supported in suspended arrangement by the roof plate 8, the rods preferably extending through the plate and having nuts 102 and 103 thereon respectively which are supported upon the top of the plate, to permit longitudinal adjustment of the rods. The hanger rods extend downward and through the ears 92 and 93 respectively and, being screw-threaded, have nuts 104 and 105 thereon respectively below the ears to permit vertical adjustment of the popping-table. The hanger rods have collars 106 and 107 120 125 130

thereon respectively arranged under the roof plate 8, and preferably they are screw-threaded to permit adjustment of the hanger rods. Also the hanger rods preferably have locking nuts 108 and 109 thereon engaging the tops of the ears 92 and 93 respectively. The popping-table has a suitable electrical heater therein which consists of a suitable composition 110 in which heater elements 111 are arranged and in connection with an electrical circuit 112 which is suitably connected with a switch-board 113 supported in the rearward portion of the main housing structure. The hanger rods are provided with guide bearings which preferably comprise collars 114 and 115 adjustably arranged on the rods, each collar being secured to the rod by means of a set-screw 116. One of the collars has lateral arms 117 and 118 thereon and the opposite collar has similar arms 119 and 120 thereon. The first mentioned arms are provided respectively with guide bearings 121 and 122 and the remaining arms have similar bearings 123 and 124, the top of each guide bearing being recessed to receive a horizontal guide rod.

An agitator of improved construction comprises a hollow main part which has a rectangular top plate 125 and downwardly extending ends 126 and 127 and also sides 128 and 129 which extend downwardly farther than the ends so as to be adjacent to the sides 94 and 95 respectively of the popping-table, being adapted to retain popping corn upon the popping-table, the top plate partially covering the popping table while the ends 126 and 127 extend across the top of the popping-table. The front and rear sides 128 and 129 are preferably provided with transparent panels 130 and 131 or have slots 132 to permit the popping operation to be seen. The end 126 has guide rods 133 and 134 rigidly fixed thereon that are slidingly guided on the bearings 121 and 122 respectively, and the end 127 is similarly provided with guide rods 135 and 136 that are movably guided on the bearings 123 and 124 respectively. The top plate 125 of the agitator is centrally provided with a yoke or cam 137 which is fixed to the plate and preferably is composed of laminated plates of suitable material to permit noiseless contact therewith, and it has a slot 138 therein extending transversely with respect to the line of movement of the agitator and receiving the crank-pin 45, whereby the agitator is reciprocated. The agitator is so adjusted and guided separately from the popping-table as to permit it to move quietly and without causing frictional resistance on the popping-table. The rearward portion of the top 125 has a longitudinal receiving aperture 139 therein that is below the feed-chute and above the higher

portion of the popping-table, and the top 125 has also a deflector plate 140 which extends downwardly in the interior towards the rear side 129 of the hollow agitator part. A suitable number of agitator rods or bars 141 are secured at their ends to the sides 128 and 129 of the agitator part so as to extend transversely adjacent to the top 89 of the popping-table, for working the corn to and fro thereon, and for convenience they may be connected with the two frame bars as seen in Fig. 15 whereby to connect them to the agitator sides. The agitator has a restrainer appliance therein which comprises a bar 142 having arms 143 and 144 which are pivoted to the ends 126 and 127 respectively, so that the bar 142 shall be located on the top 89 above the intermediate wall 96. The middle portion of the bar 142 has a lug-pin 145 thereon to which the link 88 is loosely connected, the link extending through a slot 146 in the agitator top, and preferably a coil-spring 147 is so arranged on the lug-pin as to prevent side motion of the link on the lug-pin.

A novel separator is provided for the purpose of separating the shot corn from the popped corn, and as preferably constructed comprises two end walls 148 and 149, two short side walls 150 and 151 connected to the end walls respectively and extending each towards the other, two short side walls 152 and 153 extending also from the end walls respectively and each towards the other, a low wall 154 connected to two of the short walls, and a low wall 155 connected to the ends of the remaining short side walls; and a relatively short hopper 156 is connected with the walls 154 and 155 to receive the shot corn while the popped corn may fall through the passages formed beyond the ends of the hopper by said walls. A discharge pipe 157 is connected with the forward portion of the hopper 156 and extends downward. The end walls 148 and 149 have hanger rods 158 and 159 rigidly secured to the popping-table, preferably to the intermediate wall 96. The separator has an inclined side plate 160 adjustably secured to the front walls 150 and 151 by means of screws 161 and 162, and the plate preferably has an extension lip 163 intermediate of its ends. The separator has also an inclined side plate 164 which extends nearly to the lip 163 of the opposite plate, the plates 160 and 164 constituting a slotted hopper bottom, the plate 164 being secured to the wall portions 154 and 155, being shorter than the opposite plate to permit the popped corn received onto the plate to be pushed off the ends of the shorter plate so as to fall beyond the low walls.

A novel gatherer to receive the popped corn from the end portions of the separator

is provided and comprises two sides 165 and 166 which preferably have slots 167 and 168 therein respectively, inclined bottom members 169 and 170 being connected to the 5 sides and extending downwardly each towards the other to constitute a hopper bottom with suitable space between the lower ends of the members through which to discharge the popped corn. The forward side 10 165 of the gatherer is secured to the discharge pipe 157, the gatherer being of sufficient width to receive the popped corn as it falls through the openings near the ends of the separator.

15 The machine preferably is provided with a butter-box which is interposed between the gatherer and the floor 2 of the main housing and it preferably comprises a bottom 171, a front wall 172, a rear wall 173 20 and side walls 174 and 175. The front wall is provided with a securing bolt 176 that extends through the discharge pipe 157 and has a nut 177 thereon, permitting the butter-box to be removed to be cleansed. Preferably the outside of the front wall 172 has 25 guide lugs 178 and 179 thereon in contact with opposite portions respectively of the discharge pipe to prevent tilting of the butter-box. The butter-box has a removable 30 cover comprising a flat rearward portion 180 and an inclined portion 181 sloping forwardly to support butter and popped corn and having a low wall 182 on its lower edge portion to retain surplus butter, and the 35 inclined portion has a slot 183 therein adjacent to the retaining wall through which the surplus butter may flow back into the butter-box. The butter-box cover has journal boxes 184 and 185 thereon which support 40 a rock-shaft 186 having a dipper arm 187 fixed thereto, the arm having a downwardly-extending portion 188 provided on its end with a dipper 189 adapted to draw butter up through an aperture 190 provided 45 in the cover and permit the butter to fall onto the cover. The inclined portion of the cover has a rib 191 thereon below the aperture 190 to prevent the corn from being pushed into the aperture. The rock-shaft 50 186 has a crank-arm 192 thereon extending downwardly and having a hook-shaped crank-pin 193 to which the hook 74 on the connecting-rod 73 is detachably connected, permitting the rock-shaft to be temporarily 55 operated by hand if desired.

For the purpose of manipulating the corn after it leaves the popping-table, a novel device is provided which comprises a curved base portion 194 which is rigidly secured to 60 the front plate 138 of the agitator and extends downwardly opposite to the front of the separator, and has a horizontal member 195 thereon which extends between the top of the hopper 156 and the lower portion of 65 the plates 160 and 164, the horizontal mem-

ber 195 having a finger 196 thereon which extends upward through the slotted separator bottom or narrow space between the side and bottom plates 160 and 164 of the separator. The member 195 has a downwardly extending arm 197 thereon which terminates adjacent to the butter-box cover and has a finger 198 thereon to operate below the gatherer and move the popped corn to and fro upon the inclined portion on the 70 cover to permit the corn to be buttered.

A discharge pipe extension 199 extends from the discharge pipe 157 through the floor 2 of the housing and preferably is supported by the floor, and has a hook 200 80 at its lower end to which a pail 201 may be hung to receive the shot or unpopped corn which may be carried away.

85 Preferably the interior of the stand 1 has a suitable electrical heater 202 therein provided with a circuit 203 extending through a tube 204 to the switch board 113, to provide heat, if desired, to the floor 2.

In practical use, the corn to be popped 90 is placed in the corn-box and gravitates through the discharge pipe 18, and when the feed-shaft is operated the corn is fed thereby past the adjacent elastic fingers, the corn falling to the dumping gate 75 as the feed-shaft rotates, the eccentric 95 thereon oscillates the arms 69 and 72 and the pawl 71 intermittently moves the ratchet wheel 65 whereby the controller shaft 64 is intermittently turned, so that the finger 83 first engages the projection 87 to cause upward operation of the restrainer bar 142 for releasing some of the popped corn from the popping-table. As the controller shaft rotates, the finger 83 engages the projection 82 to cause operation of the dumping gate 100 to permit a quantity of the corn to be discharged onto the popping-table through the aperture 139 in the top of the agitator. The driving shaft 41 being in operation, the agitator is moved to and fro and causes 105 the corn upon the popping-table to be agitated and gradually worked downwardly thereon, and finally released therefrom to fall onto the inclined portions of the separator on which the corn is worked to and 110 fro by the finger 196, which pushes the large popped grains of corn off from the ends of the shorter plate 164 to be received in the end portions of the gatherer, while the smaller unpopped grains fall through the 115 space between the plates 160 and 164 and into the hopper 156, from which they descend through the discharge pipe 157 to the pail 201. The popped corn descends 120 through the bottom outlet of the gatherer onto the top of the butter-box and is pushed back and forth thereon by the finger 198, while the corn takes up some of the butter 125 and finally is crowded off the cover and falls onto the bottom of the main housing. 120

As the arm 72 oscillates it causes the rock-shaft 186 to be operated so as to cause the dipper 189 to repeatedly bring up the required butter and deposit it onto the butter-box cover.

Having thus described the invention, what is claimed as new is—

1. A corn-popping machine including a housing roof, a plurality of hanger rods secured to the roof and extending downward therefrom, and a popping-table and an agitator supported by the hanger rods, the popping-table being rigidly secured to the rods and the agitator movable upon the popping-table and guided by the rods.

2. A corn-popping machine including a stationary popping-table having an inclined top provided in its lower portion with a discharge-opening, and a hollow agitator movably guided longitudinally upon the inclined popping-table top adapted to cover the corn and having a receiving aperture in its top above the higher portion of the inclined popping-table top.

3. A corn-popping machine including a popping-table, two rods rigidly secured uprightly to opposite ends respectively of the popping-table and having each a cross-arm rigidly connected thereto, and an agitator arranged upon the popping-table to cooperate therewith and having guide rods on opposite ends respectively thereof supported for longitudinal movement of the rods on the cross-arms respectively.

4. A corn-popping machine including a popping-table comprising an inclined top plate and sides and ends and also a wall extending downward from the plate, the lower portion of the top plate having a discharge-opening therein and also two oppositely inclined portions extending downwardly from opposite sides respectively of the discharge-opening and between the wall and one of said sides, and a heating element arranged under the inclined top between the wall and the remaining one of said sides and between said ends.

5. A corn-popping machine including a housing roof, a plurality of hanger rods and also a feed-chute secured to the roof and extending downward therefrom and being supported by the roof, a popping-table rigidly secured to the hanger rods and thereby supported stationarily, the popping-table having an inclined top and the higher portion of the top being arranged below the feed-chute, a hollow agitator movably arranged upon the top of the popping-table and having a top to cover the corn thereon, the agitator being guided by the hanger rods and having a receiving-aperture in its top below the feed-chute.

6. A corn-popping machine including a stationary horizontal popping-table having an inclined top plate, the lower portion

of the plate having a discharge-opening therein, upright rods secured to the popping-table and provided with guide bearings, a hollow agitator movably arranged upon the popping-table and having guide rods movably guided upon the guide bearings, the top of the agitator covering a portion of said top plate and having a receiving-aperture arranged above the higher portion of the plate, and an actuator device secured upon the top of the agitator to move the agitator.

7. A corn-popping machine including a stationary popping-table having a discharge-opening in the top thereof, the under portion of the popping-table being provided with a corn-receptacle below the discharge-opening, upright rods secured to the popping-table, bearing arms secured to the rods, a hollow agitator movably arranged upon the popping-table and having guide rods fixed on opposite ends thereof and movably guided on the bearing arms respectively, an actuator device connected with the agitator to move it upon the popping-table, and a device secured to the agitator to be operated thereby and extending into the corn-receptacle to operate therein.

8. A corn-popping machine including a stationary popping-table having a discharge-opening in the top thereof, the under portion of the popping-table being provided with a corn-receptacle below the discharge-opening, upright rods secured to the popping-table and provided with lateral arms, a hollow agitator movably arranged upon the popping-table and having guide rods fixed thereon and movably guided on the lateral arms respectively, the agitator having a cover plate provided with a receiving-aperture, an actuator device secured upon said cover plate to move the agitator, a frame in the agitator and secured thereto, agitator bars secured to the frame, a restrainer gate pivoted in the agitator, and a link to lift the gate connected therewith and extending upward through said cover plate.

9. A corn-popping machine including a housing roof, two hanger rods secured at one end to the housing roof and extending downward therefrom, a feed-chute secured to the housing roof between the hanger rods and supported solely by the roof, a popping-table below the feed-chute and secured to the hanger rods at the lower ends thereof, guide arms secured to the hanger rods respectively, a movable hollow agitator having horizontal rods extending from opposite ends thereof and movably guided on the guide arms respectively, the top of the agitator covering a portion of the popping-table and having a receiving-aperture arranged below the feed-chute, and actuating means mounted on the feed-chute and having con-

- nection with the agitator to impart motion thereto.
10. In a corn-popping machine, the combination with a feed-chute supported at its top, of a popping-table arranged separately from the feed-chute and having an inclined top with the higher portion below the feed-chute, the lower portion of said top having a discharge-opening therein, and a hollow agitator movable in co-operation with the inclined top of the popping-table and having a top plate provided with a receiving aperture therein arranged below said feed-chute and having also a deflecting plate extending downwardly at an inclination from the top plate and below the receiving-aperture.
11. In a corn-popping machine, the combination with a stationary popping-table, and a feed-chute vertically arranged above the popping-table, of a hollow agitator arranged and guided to movably co-operate with the top of the popping-table, the agitator having a top with an aperture below the feed-chute, an actuator device comprising a plurality of plates and secured upon said agitator top and having a slot therein extending transversely of the line of movement of the agitator, and a driving shaft rotatably mounted on the feed-chute and having a crank-arm adjacent to said device, said arm having a crank pin extending into said slot.
12. In a corn-popping machine, the combination with a stationary horizontal popping-table having an inclined top, of a hollow agitator part provided with means whereby it is guided to movably co-operate with the top of the popping-table, a restrainer in the agitator part comprising a gate bar arranged adjacent to the lower portion of said inclined top and having arms pivoted to the agitator adjacent to the higher portion of said top, a feed-chute vertically arranged stationarily above the popping-table, a yoke pivoted to the feed-chute to be intermittently lifted, a link connected to said gate bar and to the yoke, and means mounted on the feed-chute adapted to intermittently lift the yoke.
13. In a corn-popping machine, the combination of a stationary popping-table having an inclined top, the lower portion of said top having a discharge opening therein, a hollow agitator part having longitudinal sides extending along the upper and lower ends of said top and also transverse ends extending across said top, said agitator part having a top plate provided with a receiving-aperture, means separate from the popping-table to movably guide the agitator part, an actuator device secured to the agitator part, rods secured to the inside of the longitudinal sides of the agitator part adjacent to the popping-table, a feed-chute
- stationarily arranged above said receiving-aperture, and means mounted on the feed-chute and having connection with the actuator device to reciprocate the agitator part.
14. A corn-popping machine including a feed-chute vertically arranged, a feeding device movably arranged in the feed-chute, a gate movably supported in the feed-chute below the feeding device, a popping-table arranged below the feed-chute, an agitator upon the popping-table, and a separator arranged below and receiving corn from the popping-table and having means for separating unpopped corn from popped corn.
15. A corn-popping machine including a feed-chute vertically arranged, a feeding device movably arranged in the feed-chute, a gate movably supported in the feed-chute below the feeding device, a popping-table arranged below the feed-chute to receive corn therefrom, a separator arranged below and receiving corn from the popping-table and having means for separating unpopped corn from popped corn, and a buttering-box arranged below and receiving the popped corn from the separator.
16. A corn-popping machine including a feed-chute vertically arranged, a feed-shaft rotatably arranged in the feed-chute, a gate movably supported in the feed-chute below the feed-shaft, a popping-table arranged below the feed-chute, an agitator movably arranged upon the popping-table to co-operate therewith, a separator structure stationarily arranged below and receiving corn from the popping-table and having a slotted bottom and outlets at the ends of the bottom, and a manipulator device secured to the agitator to be operated thereby and having a member extending through and operating in the slotted bottom of the separator structure.
17. A corn-popping machine including a feed-chute vertically arranged, a feed-shaft rotatably arranged in the feed-chute a popping-table arranged below the feed chute, a separator arranged below and receiving corn from the popping-table and having means for separating unpopped corn from popped corn, a buttering-box arranged below and receiving the popped corn from the separator, a butter dipper arm movably mounted on the buttering box, and means having connection with the feed-shaft and the butter dipper arm enabling the feed-shaft to operate the arm.
18. A corn-popping machine including a feed-chute vertically arranged, a feeding device movably arranged in the feed-chute, a popping-table arranged below the feed-chute, an agitator movably arranged upon the popping-table to co-operate therewith, a separator structure stationarily arranged below and receiving corn from the popping-table and having different outlets, a buttering-box arranged below and receiving

popped corn from the separator, and a manipulator device secured to the agitator to be operated thereby and having a member to operate in the separator structure to work the corn to the different outlets, the manipulator device having also a member arranged above the buttering-box to move the popped corn to-and-fro thereon.

19. A corn-popping machine including a feed-chute vertically arranged, a feed-shaft rotatably arranged horizontally in the feed-chute, a controller shaft rotatably supported by the feed-chute below the feed-shaft, means having connection with the feed-shaft and the controller shaft enabling the feed-shaft to intermittently turn the controller shaft, a dumping gate hingedly supported in the feed-chute below the controller shaft, a popping-table arranged below the feed-chute, an agitator movable upon the popping-table to co-operate therewith, driving means to rotate the feed-shaft provided with means to move the agitator, and means co-operating with the feed-chute structure to enable the controller shaft to periodically engage and operate the dumping gate.

20. A corn-popping machine including a feed-chute vertically arranged, a feed-shaft rotatably arranged horizontally in the feed-chute, a controller shaft rotatably supported by the feed-chute below the feed-shaft, means having connection with the feed-shaft and the controller shaft enabling the feed-shaft to intermittently turn the controller shaft, a dumping gate hingedly supported in the feed-chute below the controller shaft, a popping-table arranged below the feed-chute and having a discharge chute, an agitator movable upon the popping-table to co-operate therewith, driving means to rotate the feed-shaft provided with means to move the agitator, a restrainer movably connected with the agitator to temporarily hold the corn from the discharge chute, means actuated by the controller shaft to periodically operate the dumping gate, and means connected with the restrainer and actuated by the controller shaft to periodically operate the restrainer in advance of the operation of the dumping gate.

21. In a corn-popping machine, the combination of a feed-chute, a feeder movably mounted in the feed-chute, a popping-table arranged below the feed-chute, an agitator movably arranged and guided to co-operate with the popping-table, a separator having hangers secured to and supported by the popping-table and having also an outlet channel, a discharge pipe arranged under said channel to receive unpopped corn therefrom, a gatherer secured to the discharge pipe and arranged to receive popped corn from the separator, a buttering box secured to the discharge pipe below the gatherer, and a manipulator secured to and operated

by the agitator and extending down nearly to the buttering box, the manipulator having fingers to co-operate with the separator.

22. In a corn-popping machine, the combination of a feed-hopper, a feed-chute vertically arranged below the feed-hopper, a feed-shaft rotatably arranged horizontally in the feed-chute and having a corn-receptacle in its sides elastic fingers in the feed-chute secured to opposite portions of the wall thereof and extending downward at opposite inclinations to opposite side of the feed-shaft, a dumping gate movably supported in the feed-chute below the feed-shaft, a popping-table arranged below the feed-chute, an agitator movably arranged upon the popping-table, and a series of driving appliances having connection with and rotating the feed-shaft and also having connection with and moving the agitator.

23. In a corn-popping machine, the combination with a feed-hopper, of a feed-chute vertically arranged under the feed hopper, two series of elastic fingers secured to opposite sides respectively of the upper portion of the feed-chute and extending downward, the fingers of each series extending towards the fingers of the other series, a feed-shaft rotatably mounted horizontally in the feed-chute between and in contact with the two series of fingers and having a variable-capacity corn receptacle therein, a driving shaft rotatably mounted on the feed-chute and having operative connections with the feed-shaft, a popping-table stationarily arranged below the feed-chute, a dumping gate movably arranged in the feed-chute below the feed-shaft, and a movable agitator upon the popping-table to co-operate therewith and having connection with the driving shaft to be moved thereby.

24. In a corn-popping machine, the combination with a feed-chute, and feeding apparatus and a dumping gate mounted in the feed-chute, of a popping-table arranged below the feed-chute and having a discharge chute, a separator comprising two inclined sides spaced apart, one of the sides being shorter than the other, an agitator movable upon the popping-table, a manipulator secured to the agitator and operated thereby and having a finger arranged between said inclined sides, the finger being movable to push popped corn off the ends of said shorter side and permit unpopped corn to pass between said sides, a gatherer arranged below the separator and extending under the inclined sides and beyond the shorter one of the two, and a hopper extending over the middle portion of the gatherer and under the space between said inclined sides.

25. In a corn-popping machine, the combination with a feed-chute and feeding apparatus and a dumping gate arranged in the feed-chute, of a popping-table arranged

- below the feed-chute, an agitator movable upon the popping-table, a buttering-box arranged below the popping-table and provided with a cover having an inclined portion, the lower portion of the cover having a slit therein, the cover having also an aperture therein adjacent to the upper end of the inclined portion thereof, a shaft journaled upon the cover and having a curved arm thereon to operate through the aperture, the end of the arm having a dipper thereon, the shaft being provided with a controlling device, a stirrer arranged to operate above the slit in the cover longitudinally of the slit and having connection with the agitator to be operated thereby, and means having connection with the controlling device and the feeding apparatus to be operated thereby.
26. In a corn-popping machine, the combination of a vertical feed-chute with feeding apparatus arranged therein, a controller shaft horizontally supported by the feed-chute and projecting beyond one side thereof, the projecting portion of the shaft having a lateral projection thereon, a dumping gate in the feed-chute hinged to one portion and extending downward to the opposite portion thereof and having a controlling arm thereon, a cam lever pivoted to the feed-chute and having cam projections to be engaged by each lateral projection, a link connected with the cam lever and said controlling arm, and a popping-table arranged below and receiving from the feed-chute.
27. In a corn-popping machine, the combination with a feed-chute and feeding apparatus and a dumping gate mounted therein, of a popping-table arranged below the feed-chute, an agitator movable upon the popping-table to co-operate therewith, a separator arranged under the popping-table and having a plurality of outlets, the separator having a hopper arranged below one of its outlets, the hopper being provided with a discharge pipe, a gatherer supported by the discharge pipe and extending below the remainder of the separator outlets, a buttering box arranged below the gatherer and secured to the discharge pipe, and a manipulator secured to the agitator and having a device to operate in the separator and also a device to operate in proximity to the top of the buttering box.
28. In a corn-popping machine, the combination with a feed-chute and feeding and dumping apparatus therein, of a popping-table arranged below the feed-chute and having a discharge hopper, an agitator movable on the popping-table in co-operation therewith, a separator having a frame provided with vertical discharge openings adjacent to two opposite ends respectively thereof and also an inclined side plate fixed to said frame and extending between said openings, the separator having also a relatively lower inclined side plate adjustably secured to said frame and constituting one side wall of said openings, said lower wall being arranged below said discharge chute, a hopper extending below said discharge openings, a hopper arranged below the lower end of the shorter one of said plates, and a manipulator secured to the agitator to be operated thereby and having a finger movably arranged between the lower ends of said inclined side plates.
29. In a corn-popping machine, the combination with a feed-chute and feeding and dumping apparatuses thereon, of a popping-table arranged below the feed-chute and having a discharge hopper, an agitator movable on the popping-table to co-operate therewith, a separator arranged below and receiving corn from the discharge hopper, a gatherer arranged below the separator to receive popped corn therefrom, a buttering-box arranged below the gatherer and having a top to receive popped corn from the gatherer, and a manipulator device carried by the agitator and extending nearly to said top, said device having a finger extending into the separator to co-operate therewith and having also a horizontal finger thereon extending over a portion of said top to stir the corn thereon and push the corn from the top.
30. In a corn-popping machine, the combination with a popping-table, a feed-chute arranged above the popping-table, and feeding and dumping apparatuses in the feed chute, of a buttering-box arranged below the popping-table and having two journal boxes thereon, the buttering-box having a top with apertures therein, an agitator movable on the popping-table in co-operation therewith, a rock-shaft mounted in said boxes and having a crank arm thereon and provided with a crank pin, a curved dipper arm fixed to the rock-shaft and having a dipper thereon to be carried through said apertures, an oscillatory lever pivotally supported between its ends on the feed-chute and having connection with the feeding apparatus to be operated thereby, a connecting rod pivoted to the lever and having a hook removably connected to said crank pin, and means secured to and operated by the agitator and extending nearly to the buttering-box top to manipulate the popped corn thereon.
31. In testimony whereof, I affix my signature in presence of two witnesses.
